UNITED STATES PATENT OFFICE.

ANDRES PARODI AND JOSE BORELLO, OF BUENOS AIRES, ARGENTINA.

METALLIC CURTAIN.

1,385,023.

Specification of Letters Patent. Patented July 19, 1921.

Application filed June 1, 1918. Serial No. 237,779.

To all whom it may concern:

Be it known that we, ANDRES PARODI and JOSE BORELLO, both mechanics, subjects of the King of Italy, residing at Calle Maipú 5 671, Buenos Aires, Argentine Republic, have invented an Improvement in Metallic Curtains, of which the following description, in connection with the accompanying drawings, is a specification, like characters on the 10 drawings representing like parts.

This invention relates to metallic curtains and the object thereof is to provide a durable and reliable curtain that will be easy of operation both as to the opening and closing movements thereof regardless of the thickness or weight of its movable parts.

The invention will best be understood by reference to the following description when taken in connection with the accompanying 20 drawings of one specific embodiment thereof, while the scope will be more particularly pointed out in the appending claims.

In the drawing Figure 1 represents a vertical section partly in elevation of a curtain device embodying our invention, the lowermost sections of said curtain being shown 25 partly raised, and

Fig. 2 is a partial front elevation of the curtain.

30 In the drawings 1 indicates a panel located preferably at the top of the opening wherein is to be placed a curtain embodying this invention, and behind which said curtain, herein including a series of plates or sections 2, 3, 4, and 5, is concealed in its raised position.

The sections 2, 3, 4 and 5 may be and herein are constructed of metal and arranged normally in overlapped relation, the 40 ends thereof being respectively guided in suitably stepped grooves 2', 3', 4' and 5' formed in plates 6 secured to the sides of the aforesaid opening, the ends of said grooves serving as stops for the several curtain sections when the same are down or in closed 45 position.

The several sections of said curtain are adapted to coöperate with each other during the raising and lowering of the curtain 50 and to facilitate such coöperation each section has at or near its lower edge a laterally projecting member 52, which serves as an abutment to engage the lower end of the

next upper section during said raising and lowering operation.

For the purpose of raising and lowering the said curtain sections we have provided means including suitable flexible members which are operatively connected with the lowermost section 5.

It is desirable that a safety device be provided for the curtain which will automatically operate upon the giving out of any of the parts of the curtain operating means to prevent the dropping of said sections and to lock the curtain in a certain position, and for this purpose means are provided including a series of perforations 7 herein formed in the plate 6, said perforations constituting a rack which at times is engaged by a spring 70 actuating latch 8 attached to the lowermost section 5 of said curtain. Operatively connected with said latch is a pivoted lever 9 which is carried by section 5, while to said lever is attached one of the flexible curtain 75 operating members herein consisting of ropes 10. When tension is applied to said rope the lever 9 will be slightly elevated and through the said operative connections will withdraw the latch 8 in opposition to its 80 actuating spring from engagement with said rack thus allowing the curtain to be moved freely. But when tension upon said rope is released as by breakage or otherwise the spring actuating latch will be permitted to 85 engage said latch and thus prevent further movement of the lower section of said curtain and all other sections supported thereby.

For operating the sections of said curtain we have provided in addition to the ropes 10 drums 11, one being placed at each side of the curtain but as these drums are substantially duplicates, only one is shown. One of said ropes 10 preferably that shown, 90 in addition to passing several times around its drum extends down from the opposite side of said drum and is attached to an elevator or counterbalance 12 arranged to operate in an opposite direction to that of said 95 sections, said elevator being guided by a suitable frame 13.

The drums 11 are mounted upon a shaft 14 having operative connection through beveled gearing 15 with a shaft 16. The 105 shaft 16 is provided with a worm gear 17

adapted to be driven by a worm 17' which in turn is secured to an operating shaft 18 arranged with its ends projecting beyond the inner and outer faces of the wall of the building.

The said projecting ends of said shaft 18 are made square so as to receive a crank handle 19 by which a rotary motion may be imparted to said shaft 18 and through the described connections to the drums 11 and it is within the scope and purpose of this invention to provide a casing 19' for the ends of said shaft 18 which casing may also inclose the handle 19 so as to prevent unauthorized persons from operating the same.

As will be obvious the various sections of the curtain are successively raised and lowered by the instrumentalities described and consequently the load will gradually be increased as successive sections are engaged by the abutment 5' of the preceding sections so that by the time the raising movement reaches the upper section 2 there will be considerable weight supported by the operating devices.

To overcome these variations in weight thereby to facilitate the operation of the device both during the raising and lowering operations of said curtain, we have provided automatic counterbalancing means which successively increase or decrease the weight of the counterbalance 12 in direct proportion to the variations in weight due to the picking up or dropping of said curtain sections. For this purpose the elevator 12 is provided with an upper guide 20 and a support 21 upon which counterweights 22, 23, 24 and 25 substantially corresponding in number and weight with the sections 2, 3, 4 and 5 respectively, are supported at certain times in the operation of the device.

The said weights are normally supported upon a standard 26 by suitably recessed brackets 27, 28, 29 and 30 within the recesses thereof the lower ends of said weights are retained by pivoted fingers 31, 32, 33 and 34. The upper ends of said weights are positioned by strikers 39 pivotally attached to arms 35, 36, 37 and 38 which in turn are pivotally mounted upon the standard 26, the strikers 39 being arranged to enter suitably formed recesses formed in the upper portions of said weights to prevent the said weights from tipping.

The support 21 carries a roller 40 which roller is adapted to engage the under or upper sides of the fingers 31, 32, 33 and 34 during the upward or downward movement of said elevator thereby causing the weights positioned by said fingers to be removed from or to be placed upon said elevator or counterbalance.

The operation of the curtain hereinbefore specifically described is as follows:

Assuming the curtain to be totally lowered

and the weights 22 and 23 to be resting upon their supports 27 and 28 as are the weights 24 and 25, motion is imparted to the shaft 18 by the crank handle 19 which in turn imparts movement to the shaft 16 and through the gearing 18 and shaft 14 revolve the drums 11 in a clockwise direction as viewed in Fig. 1. This movement of the drum 11 applies tension to the rope 10 whereupon the end of the lever 9 to which said rope is attached will be lifted and the latch 8 withdrawn from engagement with the rack 7 permitting the lower section 5 of the curtain to move upwardly. As this section commences to rise the roller 49 upon the elevator 12 will abut against a projection 31' on the underside of the finger 31 and cause said finger to be rocked about its pivot and move into an outwardly and downwardly inclined position. As said finger 31 moves outwardly a second projection 32' formed upon the upper side thereof, engages the lower end of the weight 22 supported thereabove and causes the lower end of the weight 22 to slide down the inclined upper surface of said finger 31 and against the support 21 of said elevator. During this operation the arm 35 by means of the striker 39 retains engagement with the upper end of said weight and prevents the same from tipping until said striker 39 is withdrawn from its recess by the downward movement of said elevator. Upon the release of said weight 22 by said striker the upper end thereof will assume a position against the upright or back piece 100 of said elevator 12 and the guide 20.

The weight 22 is transferred to the support 21 of said elevator substantially simultaneously with the upward movement of the section 5 and at the instant when the abutment upon the section 5 engages and begins to lift the section 4, the weight 23 will likewise be delivered in the above manner to the support 21 of the elevator through the operation of the finger 32 and arm 36 which are somewhat shorter than the corresponding members of the above weight supporting and transferring means in order that these members may act only upon their respective weight 23. In a similar way when the sections 4 and 5 begin to elevate the section 3, the weight 24 will be transferred from its supporting bracket to said elevator and when all of the said sections have combined to raise the section 2 the weight 25 thereof will be caused to gravitate to said elevator, thus each of the said weights will be transferred at the proper times in the operation of raising said curtain to counterbalance their respective curtain sections.

By means of the above arrangement each of the sections at the moment that they are being raised is counterbalanced by its respective weight so that when all of the sections 5, 4, 3 and 2 have finally been lifted

the weights 22, 23, 24 and 25 will counterbalance them within the elevator. Furthermore when all of the sections are lowered the said weights will be successively transferred 5 to and supported within the standard 26. When the curtain is in its raised or opened position all of the sections and weights rest or are supported by the drums 11, but in such a way that although the supporting 10 structure of the shaft 14 is adequate for the amount of weight which it has to sustain, the rotary movement of said shaft is attained without much effort owing to the equilibrium established between the sections 15 of the curtain and the counterbalancing weights.

During the lowering of the curtain the weights 22, 23, 24 and 25 which at the start are all resting on the elevator 12, will 20 be moved in a reverse order to that in which they were transferred thereto, and in the following manner: As the elevator 21 moves upwardly the strikers 39 are caused to lodge within the upper recesses of their respective 25 weights and the roller 40 carried by said elevator is operated to engage the finger of the weight toward which said elevator is approaching whereby the weight thereof will be lifted. For example in Fig. 1 the 30 roller 40 is seen approaching the finger 32 and is about to engage said finger and upon further upward movement of the elevator said finger will likewise be raised, and as it is thus moved upwardly it slightly raises 35 the end of the weight 23 moving the same from the depression formed in the upper edge of the supporting member 21. When the finger 32 has been inclined downwardly toward the supporting member 28 the weight 40 23 will gravitate downwardly thereon until it rests in the recess formed in the upper side of the supporting member 28. Simultaneously with the gravitating movement of said weight the arm 36 and its pivoted 45 striker 39 will effect an equal movement of the above end of said weight toward the standard 26 where said end will be held until further use of said weight is required.

As the elevator continues its ascent it 50 will at the proper moment cause the finger 31 of the uppermost weight to operate upon said weight and likewise the striker 39 of the arm 35 will be introduced into the recess of said weight and in the manner previously described the weight 22 will be 55 transferred to its supporting member 27 where it likewise will remain until further use thereof is required.

It will be evident that the number and

size of the sections and hence of the weights 60 may be varied in accordance with the size of the opening it is to cover.

While I have herein shown and described merely for illustrative purposes one specific embodiment of my invention, and have disclosed and discussed in detail the construction and arrangement incidental to such disclosure, it is to be distinctly understood that the invention is limited neither to the mere details or relative arrangement of the parts 65 70 nor to the specific application herein shown, but that extensive variations from the illustrations may be made without departing from the principles thereof.

Claims—

75

1. A curtain device having a series of relatively movable coöperating sections, abutments on said sections adapted to engage another section, a revoluble drum, means operatively connecting the lowermost 80 section with said drum, means to revolve said drum to successively raise and lower said sections, a counterbalance connected with said drum and movable in a direction opposite to that of said sections, and means 85 automatically to increase and decrease the weight of said counterbalance in proportion to the increase or decrease in the weight of said sections.

2. A curtain device having a plurality of 90 coöperating sections, means successively to raise and lower said sections, and means automatically to counterbalance said sections including a lifting cage arranged to move in a direction opposite to that of said 95 sections, said means also including a series of weights adapted successively to be transferred to and gravitate with said lifting cage as each of said sections is lifted.

3. A metallic curtain having a plurality 100 of coöperating sections, means to guide the ends of said sections including a plate provided with a plurality of stepped grooves, means progressively to raise said sections from and lower to their respective steps, 105 counterbalancing means for said sections, and means automatically to increase and decrease the weight of said counterbalancing means in proportion as said sections are picked up or dropped.

In testimony whereof we have signed our names to this specification.
